ATTORNEY

UNITED STATES PATENT OFFICE

CLAUDE F. MARTIN, OF PAXTON, ILLINOIS.

LETTER-HOLDER.

1,220,251.

Specification of Letters Patent.

Patented Mar. 27, 1917.

Application filed June 1, 1916. Serial No. 101,129.

To all whom it may concern:

Be it known that I, CLAUDE F. MARTIN, a citizen of the United States, residing at Paxton, in the county of Ford and State of Illinois, have invented certain new and useful Improvements in Letter-Holders, of which the following is a specification.

This invention relates to an improvement in letter holders, and more particularly to a device of this nature which is adaptable for use in connection with boxes such as are used on rural delivery routes.

An object of my invention is to provide a holder which may be attached and fitted in place in the boxes as manufactured, or which may be sold as a separate attachment to be applied by the user, and which is so constructed that it may be fitted and used in conjunction with practically any of the standard and approved types of rural delivery boxes.

A further object is to so construct the device that as the door of the box is opened the holder will be extended from the box and thus the device will be particularly well adapted for the keeping and holding of a letter which is to be taken by the postman by reason of the fact that the holder will present the letter conspicuously to his attention immediately the box is opened.

With the above and other objects in view, my invention consists in such novel features of construction and combinations of parts which will be hereinafter set forth in connection with the drawings and then more particularly pointed out in the claims.

In the drawings:

Figure 1 is a view in longitudinal vertical section through a mail box with the device of my invention fitted in an operative relation therein.

Fig. 2 is a detail sectional view on the line 2-2 of Fig. 1.

Fig. 3 is a view in perspective of the track way in which the holder is mounted to be capable of movement.

The numeral 1 designates the mail box as an entirety, which is mounted in any suitable manner as for instance on the supporting standard or post 2, and this box has the door 3 thereof hinged at one end in such relation that as the door is opened it has upward swinging movement.

A trackway 4 which may be constructed from a strip of sheet metal having the edges

thereof bent over to form the overhanging flanges 5 and 6 is provided with the openings 7 adjacent to the ends thereof through which rivets, bolts, or other suitable fastening means may be passed to secure the trackway to the inner side of the box. As is shown in Fig. 1, the trackway 4 is secured in horizontal disposition adjacent to the bottom of the box and along one of the side walls thereof with one end adjacent to the door opening. A slide bar 8 is made of substantially the same length as the trackway 4 and is received in the trackway to have an easy sliding fit therewith and to be held against lateral displacement by the overhanging flanges 5 and 6.

A spacing block 9 is mounted on the bar 8 adjacent to one end thereof and a plate 10 is connected on the spacing block 9, the block being sufficiently thick that the plate 10 is held out of contact with the flanges 5 and 6 when the bar 8 is moved inwardly to the position entirely adjacent to the trackway 4 and to have the edges thereof entirely confined by the flanges 5 and 6. A gripping member 11 is mounted on suitable bearings 12 provided on the outer face of the plate 10 so that this gripping member 11 will be capable of swinging movement, and a spring 13 is mounted to bear beneath one end of the gripping member 11 beyond the pivotal mounting thereof to hold the upper end of the member 11 normally resiliently pressed against the upper portion of the plate 10. By arranging the parts as set forth, a spring 14 is provided on the outer end of the bar 8 and by depression of the thumb piece 14, the gripping member 11 may be swung against the tension of the spring 13 to open the jaw of the clip.

A bearing bracket 15 is mounted on the slide bar 8 adjacent to the inner end thereof, and a bearing bracket 16 is adapted to be connected with the door 3 on the inner side thereof. A link 17 is shaped on its end to have bearing portions which are received in bearing openings of the bearing brackets 15 and 16, and thus a connection is established from the door 3 to the slide bar 8.

As has been stated, this structure might all be embodied in the mail box as manufactured or the device might be constructed as an attachment to be fitted to the box by the individual user. In the use of the device letters or other mail matter will be

fitted to be held by the spring clip in substantially the relation shown by the dotted lines of Fig. 1. To preclude the possibility of the link 17 engaging with the mail matter and interfering with the proper working of the device in either the opening or the closing of the door, it is preferable that the bracket 15 be so constructed that the link 17 will be thrown over somewhat from the slide bar 8. When the mail matter is to be held and displayed to the postman for collection, it will be fitted in the clip at the outer end of the slide bar when the door 3 is open and then by closing movement of the door 3 sufficient movement will be imparted to the slide bar 8 through the link 17 that this slide bar will be moved to the trackway to carry the mail matter to be entirely within the box and the closing of the door will close the box against unauthorized removal of the mail matter. As the door 3 of the box is opened by the postman, a reverse action of the parts takes place and in consequence the slide bar 8 is moved out to display the mail matter held by the clip and to permit ready removal thereof.

While I have herein shown and described only one specific form of the device, it will be understood that changes and modifications might be resorted to in the various parts and in the arrangement of the same without departing from the spirit and scope of my invention, and hence I do not wish 35 to be limited to the exact disclosures but only to such points as may be set forth in the claims.

I claim:

1. An attachment for mail boxes having a hinged door for closing the same comprising a slide bar, a trackway to be secured to the inner wall of the body of the box to support the slide bar and permit movement of the same to extend from the box, means 45 carried by said slide bar to hold mail matter, and a connection from said slide bar to the door arranged to impart extension

movement to said slide bar as the door is opened.

2. An attachment for mail boxes comprising a trackway to be secured upon the inner wall of the body of said box, a slide bar mounted in said trackway, a letter holding clip carried by the outer end of said slide bar, a bracket to be connected with the door of the box, and a link connected between said bracket and the slide bar to impart movement to the slide bar as the door is opened and closed.

3. An attachment for use in connection with mail boxes having the door thereof hinged, comprising a trackway to be secured to the inner wall of the body of the box adjacent to the door and with one end opening in proximity to the opening to be closed by the door, a slide bar mounted in said trackway, a letter holding clip mounted on the outer end of said slide bar, a bearing bracket to be secured to the inner side of the door, a bearing bracket mounted on the slide bar, and a link connected between said bearing brackets to cause movement to be imparted to the slide bar as the door is opened and closed.

4. In combination with a mail box having a door hinged at one end thereof, a track way mounted on one of the inner side walls of the body of the box, a slide bar mounted in said track way to be capable of movement therein to extend from the box when the door is open, a letter holding clip mounted on the outer end of said slide bar to receive and hold mail matter, a bearing bracket secured on the inner side of the door, and a link connected between said bearing bracket and the slide bar to move the slide bar within the track way as the door is opened and closed.

In testimony whereof I affix my signature in presence of two witnesses.

CLAUDE F. MARTIN.
